UNITED STATES PATENT OFFICE.

JOHN W. LITTLE, OF McCOOK, NEBRASKA.

BEET TOPPER.

Application filed February 24, 1922. Serial No. 538,982.

To all whom it may concern:

Be it known that I, JOHN W. LITTLE, a citizen of the United States, residing at McCook, in the county of Redwillow and 5 State of Nebraska, have invented certain new and useful Improvements in Beet Toppers, of which the following is a specification.

This invention has reference to harvesters and particularly to those of a type 10 adapted to the topping of certain vegetables such as sugar beets.

The primary object of the invention is to generally improve the construction and 15 operation of the machine by providing cutting means automatically adjusted, by the beet or object to be cut, to the proper height for topping and by retaining the cutting mechanism in position to complete 20 the topping cut before being shifted to a higher or lower level.

An additional object is to provide a beet 25 topping machine in which the topping mechanism is preceded by a pilot or gauge, traveling in advance of the cutting knives and movable by the beet or other object to be cut, said gauge being connected by levers to the cutting knives for raising same to the proper height with the object to be 30 topped.

Various other objects and advantages of the invention will become apparent as the description proceeds.

In the drawings:

35 Figure 1 is a top plan view of the improved beet topper.

Figure 2 is a vertical longitudinal section therethru as taken on line 2—2 of Figure 1.

40 Figure 3 is a rear end view of the machine.

Figure 4 is a vertical cross section thru the frame thereof as indicated by line 4—4 of Figure 1.

45 Figure 5 is a detail of the cutting mechanism, and

Figure 6 is a detailed sectional view of the cutting knives.

The machine embodies a frame 10 50 mounted on an axle 11 which is supported by wheels 12. Rotating with the axle is a gear 13 which drives gear 14 thru the medium of pinion 15. A sprocket 16 mounted on a shaft which is geared to member 14, propels sprocket chain 17 that crosses over idler 18 and sprocket 19.

Sprocket 19 is mounted at one end of shaft 20, supported in suitable hangers 21 depending from the frame of the machine, and having a pitman 22 at the other end. 60 This pitman operates the cutting or topping mechanism of the machine when the various gears are rotated by the turning of the axle.

The topping mechanism embodies a stationary saw-tooth knife 23 and a movable knife 24 of similar construction, connected by slotted guides 25. Knife 24 is joined at 65 26 to the pitman for reciprocation longitudinally of stationary knife 23 when the 70 machine is in motion and to facilitate the cutting or shearing action of the knives, each of the latter is beveled on its outer side to its teeth, as seen in Figure 6. 75 Guides 25 are integral with cutter frame 27 which slides in vertical guides 28 depending from the frame of the machine as shown.

In the harvesting of sugar beets it is important that the tops and crowns be cut and 80 separated from the beet at the base of the crown, which varies according to the height the beet projects above the ground. In the present invention this is accomplished by a gauge 29 carried by a rocker frame 30 85 which is pivoted to frame 10 as at 31. This gauge consists of three rolling colters mounted on a shaft and so spaced as to cut or sink into or through the beet top to the crown. The rocker frame is composed of 90 two U-shaped side members suitably connected by cross braces so as to move as a unit. Fastened to frame 10 and extending up over rocker 30 is a yoke 32 from which depends a spring 33 attached at 34 to the 95 rocker for resiliently supporting the same.

At its upper end each U-shaped member of the rocker is connected by a link 35 to a lifting lever 36. Each lifting lever 36 is pivoted to the frame of the machine at a 100 point rearwardly of the guides 28, as shown at 37, and is connected by a chain 38 to the lower end of cutter frame 27. When these levers, of which there are two, are swung upwardly about their pivots, the cutter 105 frame is adjusted upwardly in its guides, and when the levers are lowered the cutter frame slides downwardly in the guides. This adjustment is automatically effected when gauge 29 is moved upwardly by the 110 beet or other object engaged thereby since the tilting of the rocker on its pivot ad-

justs the cutter frame vertically thru the leverage provided by elements 35 and 36.

Hence, it will be seen that the cutting mechanism may be shifted either to a higher or lower level according to the height the beets project above the ground. The leverage thus provided is sufficient to not only raise the cutting knives to the proper contact with the object to be topped but also to retain that contact until the topping cut is completed before engaging or shifting the knives to another position.

To enable the operator to raise the entire mechanism off the ground when leaving the field, a manually-operated lift is provided and consists of a crank shaft 39 rotatably mounted in bearings 40 of the frame and connected by link 41, to a lever 42. This lever is pivoted to a bracket 43 and provided with a catch 44 engageable in the notches of the ratchet to lock the lever in any adjusted position.

Projecting outwardly from shaft 39 approximately at right angles to the crank thereof is a lug 45 to which is fastened an extension 46. Connected to the end of the extension is a chain 47 which fastens to cross-brace 48 of rocker 30. This chain tilts the rocker upwardly when lever 42 is drawn back to raise the mechanism off the ground. The chain also provides a flexible connection between the rocker frame and the manually-operated lift of sufficient laxness to permit the automatic tilting of the rocker frame by movement of the gauge independently of and without interference from the manually-operated lift.

It will thus be seen that during the operation of the machine the cutting knives sever the tops and crowns from the beets when brought in contact with the latter and that proper contact is insured by the movement gauge and leverage means which shift the cutting mechanism to the proper height.

From the foregoing it is believed that the construction and operation of the machine can be readily understood, and that further description is deemed unnecessary.

What is claimed is:

1. A beet topper including a supporting frame presenting vertical guides, a cutter mechanism slidable in said vertical guides, a rocker pivoted to the supporting frame in advance of the cutter mechanism, a gauge

wheel mounted at the lower end of the rocker, a lever having one end pivoted to the supporting frame and its other end pivotally connected with the upper end of the said rocker, and means connecting the said lever with the lower end of the said cutter mechanism.

2. A beet topper including a main frame presenting vertical guides, a cutter frame slidably positioned within the said guides, a cutter at the lower end of the said cutter frame, a rocker frame pivoted to the main frame in advance of the said guides, colters at the lower end of the rocker frame, lifting levers pivoted to the main frame rearwardly of the said guides, links pivotally connecting the said levers with the upper end of the said rocker frame, and chains connecting the said lifting levers to opposite lower ends of the cutter frame.

3. A beet topper including a main frame presenting vertical guides, a cutter frame slidable in the said guides, a rocker pivoted to the main frame in advance of the said guides and presenting a U-shaped member, a gauge wheel at one terminal of the U-shaped member, a lifting lever having one end pivoted to the main frame at a point rearwardly of the said guides and having its other end pivotally connected to the opposite terminal of the U-shaped member whereby it is raised and lowered by the movement of the said rocker, and lifting chains connecting the lower end of the cutter frame with the said lever.

4. A beet topper including a main frame presenting vertical guides, a cutter frame slidable in the said guides, a U-shaped rocker pivoted to the main frame in advance of the said guides, gauge wheels at the lower end of the said rocker, a crank shaft journaled in said frame, a connection between the said crank shaft and the upper end of the said rocker, a lever for turning the said crank shaft to operate the said rocker, a lifting lever having one end pivoted to the main frame rearwardly of the said guides and having its other end pivotally connected to the upper end of the said rocker, and a chain connecting the said lever with the lower end of the said cutter frame.

In testimony whereof I affix my signature.

JOHN W. LITTLE.
